(57) **CLAIM**

The ornamental design for a hybrid hand covering with index finger distal phalanx fingertip segment as shown and described.

DESCRIPTION

FIG. 1 is a perspective view of a left-hand embodiment of a hybrid hand covering with index finger distal phalanx fingertip segment showing my design, it being understood that a right-hand embodiment is a mirror image thereof and of the following views;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof; and,

FIG. 7 is a rear elevation view thereof.

The dash-dash broken lines illustrate portions of the hybrid hand covering with index finger distal phalanx fingertip segment and form no part of the claimed design. The dash-dot broken lines illustrate boundaries of the claim and form no part of the claimed design.
